UNITED STATES PATENT OFFICE.

EMERSON H. TOMPKINS, OF WATERBURY, CONNECTICUT, ASSIGNOR TO SCOVILL MANUFACTURING COMPANY, OF WATERBURY, CONNECTICUT, A CORPORATION OF CONNECTICUT.

DESIGN FOR A COSMETIC-STICK HOLDER.

Application filed January 26, 1924. Serial No. 8,438. Term of patent 7 years.

To all whom it may concern:

Be it known that I, EMERSON H. TOMPKINS, a citizen of the United States, residing at Waterbury, county of New Haven, State of Connecticut, have invented a new, original, and ornamental Design for a Cosmetic-Stick Holder, of which the following is a specification.

This invention relates to a new, original and ornamental design for a cosmetic stick holder, and the invention consists in the peculiar shape or configuration of the same, substantially as shown in the accompanying drawing forming a part of this specification, in which—

Figure 1 is a side view of a cosmetic stick holder showing my new design, and Figure 2 is an end elevation of the same.

I claim—

The ornamental design for a cosmetic stick holder as shown.

In testimony whereof I have hereunto set my hand.

EMERSON H. TOMPKINS.
